UNITED STATES PATENT OFFICE

100,792

DESIGN FOR A CARVING TONG

Bryant W. Pocock, Algonac, Mich.

Application June 10, 1936, Serial No. 63,197

Term of patent 14 years

To all whom it may concern:

Be it known that I, Bryant W. Pocock, a citizen of the United States, residing at Algonac, in the county of St. Clair and State of Michigan, have invented a new, original, and ornamental Design for a Carving Tong, of which the following is a specification, reference being had to the accompanying drawing, forming part thereof.

I claim:

The ornamental design for a carving tong, as shown.

BRYANT W. POCOCK.
